UNITED STATES PATENT OFFICE.

LEROY LAWSON, OF TIPTON, INDIANA.

VISION SHIELD FOR VEHICLES.

1,427,605.

Specification of Letters Patent. Patented Aug. 29, 1922.

Application filed May 5, 1921. Serial No. 467,181.

To all whom it may concern:

Be it known that I, LEROY LAWSON, a citizen of the United States, and a resident of Tipton, county of Tipton, and State of Indiana, have invented a certain new and useful Vision Shield for Vehicles; and I do hereby declare that the following is a full, clear, and exact description thereof, reference being had to the accompanying drawings, in which like numerals refer to like parts.

This invention relates to a vision shield for vehicles supplementing the usual wind shield or window.

15 The chief object of this invention is to provide a window or wind shield of the vehicle with a vision shield which may be secured to said window or wind shield as an attachment.

20 The chief feature of the invention consists in associating the vision shield with the window in such a manner that said shield may be adjustably positioned and maintained in position upon said window and simultaneously is adapted to discharge the water collected by said shield from the shield and window, as well as adapted to clean the window.

Another feature of the invention consists 30 in the particular means for mounting and supporting the shield upon the window.

The full nature of this invention will be understood from the accompanying drawings and the following description and 35 claims.

In the drawings Fig. 1 is a side elevational view of the vehicle with the vision shield associated therewith. Fig. 2 is an enlarged front elevation of a window with 40 the shield associated therewith. Fig. 3 is a longitudinal sectional view of the window and shield shown in Fig. 2. Fig. 4 is an enlarged bottom plan view of the shield. Fig. 5 is an enlarged view of the supporting 45 means for the shield.

In the drawings 10 indicates a vehicle, such as an electric railway car and 11 designates the driver's or motorman's compartment provided with a plurality of windows 50 12, one of which is centrally positioned. One of the windows 12, see Fig. 2, is herein shown comprising the usual frame or sash 13 and the usual transparent member or pane of glass 14.

55 The vision shield is herein designated by the numeral 15, and comprises a frame work

16 which includes two parallel sides 16^a. Also positioned upon the frame work, and preferably medianly thereof, upon the upper side is a bracket 17 associated with which is 60 a cord or cable 18. Each of the sides 16^a of the frame 16 is provided with a plurality of outwardly extending flanges or brackets 19 suitably secured thereto. Adjustably, yet rigidly, secured to the sash 13 of the window is a pair of guides 20 having the slots 21 therein, which guides are substantially parallel and have their slots facing each other. The guides extend substantially across the window and each of the brackets 19 terminates in a ball retainer 22 which is seatable in said guide, the flange or neck portion 23 thereof extending through the slot 21 in the guide. Within each guide and beneath the lowermost walls 22 is a coil 70 spring 24, one end of which is suitably secured to the base of said guides or to the sash, and the other end suitably secured to the shield frame, or to the lowermost balls 22. Thus, the spring normally tends to draw 80 the vision shield downward. The cable 18, therefore, is adapted to maintain the vision shield in the desired position through means of any preferred or usual form, such as that illustrated in Fig. 5, wherein there is shown 85 the usual self locking pulley 25 associated with the cable 18 and a suitable knob or handle 26. Other means may be provided for maintaining the cable in the desired position to maintain the vision shield in adjusted position upon the window.

Reference will now be had to Figs. 2 to 4 inclusive wherein the particular construction of the vision shield is illustrated in detail. The vision shield comprises an outwardly and downwardly extending portion 30 which portion may be of any suitable material, but preferably is of glass and may be colored to serve as a sun shield. The portion 30 extends angularly of the window 14 95 and preferably is in the form of a portion of a conical surface. However, the lowermost and outer edge 31 of the shield is arcuate in form and extends downwardly and rearwardly towards the window. The lower 100 edge of the vision shield is provided with a trough portion 32 which is shown clearly in Figs. 2 and 3 and is adapted to collect the water which is impinged upon the shield 30 and turn the same from said shield, discharging the same outwardly therefrom and 110 from the window, so that no water will

drain from the lower edge of the shield and be thrown against the central portion of the pane 14. The panels 30^a may be colored or transparent glass or other suitable material.

5 The top edge of the frame or sash 16 is provided with a retaining portion 33 in which is positioned suitable means such as the rubber strip 34 which lies flush against the pane 14 and in the upward sliding movement of said shield structure said rubber strip 34, which extends transversely of the window 14, is adapted to clean said window as well as prevent the passage of water which impinges upon the upper portion of the pane 14 not protected by the shield from passing downwardly on said pane. Thus, the strip 34 forces the water which impinges upon the upper portion of the pane 14 to be deflected from said pane on to said shield 20 and thus be discharged by the trough as heretofore described.

The invention claimed is:

1. The combination of a window, a shield therefor, including two parallel sides, a pair of guides secured to said window in spaced

and parallel relation and at opposite sides of the shield, guiding means on each of the parallel sides of said shield and seated in and slidable in said guides, means for sliding the shield in said guides in one direction, and other means for sliding said shield in the opposite direction.

2. The combination of a window, a shield therefor, including two parallel sides, a pair of guides secured to said window in spaced and parallel relation and at opposite sides of the shield, projecting guiding means on each of the parallel sides of said shield and seated in and slidable in said guides, spring means in each of said guides cooperating with the projecting guiding means of said shield for moving the shield in one direction, other means associated with said shield for moving the same in the opposite direction, and means for securing said last mentioned means to retain said shield in the selective positions upon said window.

In witness whereof, I have hereunto affixed my signature.

LEROY LAWSON.
